(57) **CLAIM**

The ornamental design for a digital camera, as shown and described.

DESCRIPTION

FIG. 1 is a rear, right and top perspective view of a digital camera, showing my new design;

FIG. 2 is a front, left and bottom perspective view thereof;

FIG. 3 is a rear, right and top perspective view, shown with the digital camera in an open status;

FIG. 4 is a front view thereof, shown with the digital camera in a closed status;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines shown in the drawings illustrate portions of the digital camera that form no part of the claimed design.
